DUAL STRIP FEEDING AND BRAKING DEVICE

Frank J. Furman, Endicott, N. Y., assignor to
International Business Machines Corporation,
New York, N. Y., a corporation of New York

Application May 27, 1948, Serial No. 29,534

6 Claims. (Cl. 197—133)

1

This invention relates generally to improvements in paper feeding devices and more particularly to controls over feeding in connection with dual paper strip advancing means on a card controlled tabulator.

An object of the invention is the provision of dual pin feed devices assembled as a unit, each device having a separate tape controlled drive for independent differential adjustment, said unit being removable from the platen, the two tape controlled drivers, and the remainder of the carriage.

Another object of the invention is the provision of separate paper feed brakes or adjustable drags which cooperate with the two webs of paper, or two sets of strips, as they come from the source of supply and before they pass around the platen. After the paper passes around the platen, it is engaged by the pin wheels which advance it after each printing impression. In other words, the brake or drag cooperates with the paper before it reaches the platen and the pin wheel pulls the paper beyond the platen. Therefore, the drag serves to keep the paper taut on the pin wheel and around the platen, and also serves to prevent buckling, looseness, or piling up of the webs at either the platen or the wheel.

Another object of the invention is to make the brake or drag adjustable so that the pressure on the web and the retarding influence thereof may be varied according to the extent and speed of the feed or according to the thickness of the pack of sheets. Not only is the brake adjustable, it is also settable to an "off" position to free the paper from restraint.

Another object of the invention is the coordination of an "end of sheet" control with the brake device so that card feeding is stopped when the end of a record strip passes the braking position and before it reaches the printing position at the platen. In one of two "brake off" positions, the brake devices serve to disable the "end of sheet" controls so that then the controls do not serve to detect a missing sheet. There are three control positions of a brake lever wherein joint control is exercised over the brake and the end of sheet controls. There is the first position designated as "brake on" and end of sheet "control on." This is the normal running condition wherein long feeding requires the brake and the operator wishes to be relieved of watching for the end of the paper web. The second position of the brake lever is designated "brake off" and end of sheet "control on." This control is provided

2

for a condition of sheet feeding, or exclusive line spacing feed, or short extents of feed which are known to involve no tendency for the paper webs to overdraw the web from the supply source and no condition of buckling or jutting off the pins. However, the end of sheet control is then retained to detect depletion of the paper and stop card feeding. The third position of the brake lever is designated "brake off and control off." This control is provided for starting conditions when it is desired to thread webs of paper through the braking and detection control positions without interference. It is also useful for printing on short forms when it is known that the few items will find room on the sheet even though the end of it passes the braking position before all cards are sensed and it is desired that card feeding continue till the end of the sheet is near or at the platen. The third position is also used when sheets are to be advanced by the platen alone independently of the pin feed, at which time the ordinary pressure rollers exert control over the position of the record sheets.

Other objects of the invention will be pointed out in the following description and claims and illustrated in the accompanying drawings, which disclose, by way of example, the principle of the invention and the best mode, which has been contemplated, of applying that principle.

In the drawings:

Fig. 1 is a plan view showing the dual feed carriage with the pin feed wheels and the braking devices. The two tape controlled differential drive units are also shown, the one on the right being connected by gearing to the platen and the lower pair of pin feed wheels for the inner strip, and the unit on the left being connected by gearing to the upper set of pin wheels for the outer strip.

Fig. 2 is a side elevation view taken along line 2—2 in Fig. 1 and showing the pairs of brakes and "end of sheet" detector levers and the pair of brake setting levers.

Fig. 2a is a detail view of the brake setting lever in the second position wherein the brake is off.

Fig. 2b is a detail view of the brake setting lever in the third position wherein both the brake and the end of sheet control are off.

Fig. 3 is an enlarged perspective view of the brake setting lever and the connections thereto from to the brake and the sheet end detector lever.

Fig. 4 is a sectional plan view of the brake setting lever as seen along line 4—4 in Fig. 2b.

Fig. 5 is a sectional elevation view taken along

line 5-5 in Fig. 1 and showing the paths of both webs of paper as they pass around the platen and separate pin feed wheels. The contacts operated by the two "end of sheet" levers are also shown in this view.

Fig. 6 is a wiring diagram showing the "end of sheet" controls with the relays for governing the card feed clutch magnet.

Referring to the plan view, Fig. 1, it is seen that the platen P is supported between two main carriage frames 20 and 21. Above the platen P are two pairs of pin wheel feed units for advancing the two record strips. The lower pair of pin wheels LPL and LPR, Fig. 5, engage the marginal perforations of an inner, secondary or register strip R, the path of which is shown by R-R in Fig. 5. The upper pair of pin wheels UPL and UPR engage the marginal perforations of an outer, main or check strip M, which may have a carbon backing or be fed with a carbon sheet, and the path of which is shown by M-M in Fig. 5. It is noted that both strips pass together around the front of the rotatable platen P and it is at the printing line PL that type impressions are effected in common on both records.

The pin wheel units illustrated are of the twist-
ing pin variety such as shown in the Paris Patent
2,315,731 which can be referred to for details of
construction.

Turning back to Fig. 1, it is observed that separate motor driven feed control units UTC and LTC are provided for the upper and lower pin feed units, respectively. These feed controls are of the perforated tape controlled type such as illustrated in detail in the patent application of Mills et al., Serial No. 609,854, filed on August 9, 1945, now Patent No. 2,531,885, November 28, 1950. It is sufficient to note here that the right tape controlled unit LTC contains a motor M, the worm shaft W of which, engages a gear train G connected to high and low speed clutch devices CD which operate a second gear train G' with drive connections to the platen P. On the platen shaft is a gear 16 in mesh with an idler gear 17 which meshes in turn with a gear 18 fastened to a shaft 19 of the lower pin wheel units LPL and LPR.

The other tape controlled feed unit UTC contains the same sort of motor, gears and clutch parts as noted in describing unit LTC, the only difference being that they are reversed in position and include an extra idler gear 22 which provides an elevated driving source in mesh with a pinion 23 fastened to the left end of a shaft 24 passing through the upper pin feed units UPL and UPR.

Therefore it is clear that the right hand drive unit LTC rotates the platen P and the lower pin feed wheels, while the left hand drive unit UTC rotates the upper pin feed wheels.

Attached to the inside of the main side frames 20 and 21 are the side plates 29 and 30 of a removable frame which carries both sets of pin wheels. The lower pin wheels are on shafts fixed in position between plates 29 and 30, but the upper pin wheels are in a separate subassembly comprising rockable side plates 31 and 32 which are loosely and pivotally mounted on the large side plates 29 and 30. The upper wheels are so mounted, in order that they may be swung upward and locked in an elevated position before paper is threaded over the lower pin wheels. Not only is the upper pin wheel assembly rockable, but it is also possible to remove it without the use of tools because of the pin and open slot connec-

tion to the lower frame which is about to be described.

In Fig. 5 it is seen that side plate 29 supports shafts 33 and 34 in addition to shaft 19 of the lower pin wheel units. A key 35 is in shaft 19 and serves to connect the wheel portion of the pin feed unit to shaft 19 regardless of the lateral position in which it is placed. A U-shaped frame 36 embraces the pin feed unit and has slotted tails 37 engaging shaft 33, thereby providing a relatively stationary part of the unit to which is attached the fixed pinion holder for twisting the pins.

Confined between the tails 37 is an adjustment block 38 slidably mounted on shaft 33. Into the block there projects a thumb screw 39 which may be loosened to release the pin feed unit for lateral adjustment according to width of record strip, and then tightened to hold the unit in place.

On a screw 40 in frame 36 there is pivoted a curved strip guide 41 for holding the record material down on the pins. An over center spring 42 serves to hold the guide 41 in either a lowered operating position, or a raised "off" position which is occupied while forms are being assembled in the carriage.

Between each pair of pin wheel units is a pair of paper supports 44. They are curved at a tangent to the periphery of the pin wheels and bent down with side walls loosely encircling the feed unit shafts, so that they are slidable into positions to support the record material intermediate the pin wheels at the margins. The lower supports 44 are held on, and slideable along, shafts 33 and 34; while the upper supports are similarly held on corresponding shafts 45 and 46 of the upper feed unit.

The parts of the upper pin wheel assembly involving shafts 24, 45 and 46 are similar to those described in connection with the assembly of the lower pin wheels on shafts 19, 33 and 34. Before going into detail regarding the manner of mounting the upper unit on the main feed frames 29 and 30 and the manner of fastening the feed frames to the carriage frames, it is believed well to point out the parts and appendages of the carriage frames.

In Fig. 5 it is seen that a heavy bar 48 ties together the main carriage frames 20 and 21 and is secured to a cross bar 49 of the tabulator. Extending between the main frames is a slanted paper table 50 to the lower end of which is attached a thin continuation piece 51 which extends down to the lower part of the platen P and is curved part way around to the front. Resting on tables 50 and 51 is a pair of side guides 52 the upper ends of which are slidably mounted on a cross shaft 53.

At the front of the main frames are bearings for carrying the ends of the platen shaft 14. Co-operating with the platen P are sets of upper and lower pressure rollers 55 and 56. The upper rollers 56 are on a rod which is part of a bail comprising side arms 57 and a fulcrum shaft 58.

Attached to the ends of shaft 58 are latch arms 59 which catch in grooved ends of shaft 33 to hold the entire pin feed frame assembled on the main frames. For the purpose of holding the pin feed devices, each main frame 26 and 21 is formed with a vertically slotted fork 61 and a hook shaped extension 62. In the assembled position of the pin feed devices, extending ends of shaft 34 are caught under hooks 62 and, at the same time, shaft 33 is snapped in the slot of fork 61.

and under the retaining ends of arms 59. A spring (not shown) urges the bail 57 and arms 59 in a counterclockwise direction to hold down the ends of shaft 33 and retain the pin feed devices with the frames 29 and 30 locked down.

In order to remove the pin feed devices as a unit, all that is necessary is to lift the front end of bail 57 to rock arms 59 backward, then raise the front end of the pin feed devices to lift shaft 33 out of fork 61, and then slide the whole unit backward to shove shaft 34 out from under hooks 62.

There are times when it is desired to either raise the upper pin feed devices for paper threading purposes, or to remove the upper devices entirely when only one pin feed shaft is to be used. For these purposes the upper unit is made as a separable assembly within side plates 31 and 32. The upper edges of side frames 29 and 30 are shaped to receive and retain shaft 45 and studs 64 extending inwardly from side plates 31 and 32. A hook shaped extension 65 engages stud 64 and a depression 66 is shaped to receive shaft 45. In order to hold the upper frame in position on the main feed unit frames, a pair of detent levers 67 are pivoted at 68 on the frames 29 and 30. These levers 67 are formed with notches 69 and 70 which engage extending ends of shaft 46. A spring 71 tends to rock lever 67 counterclockwise and clamp the lever against the shaft 46.

If it is desired merely to raise the upper pin wheels, then the upper unit is rocked clockwise, Fig. 5, with studs 64 as centers of rotation, and the shaft 46 is snapped into notches 70 of levers 67. With the upper unit so held, the upper pin wheels are high above the lower pin wheels with room enough between them to adjust the paper on the lower wheels. By merely pressing down on the front of the upper unit it is possible to rock the unit back to the normal position wherein shaft 46 snaps into notches 69 as shown.

When the upper unit is to be removed entirely, it is pushed rearwardly to shove studs 64 out from under hooks 65. Then, by raising the front end of the unit and drawing it forwardly, shaft 46 is disengaged from detent levers 67.

Levers 67 are held in position by stop pins 72 on side frames 29 and 30, and thus are held in position to receive the rear of the unit when it is reinserted. To replace the top unit, the shaft 46 thereof is placed in the notches 69 of levers 67, and then the unit is pushed rearwardly and at the same time swung counterclockwise until studs 64 snap under hooks 65.

The foregoing section of this description deals mainly with the means for engaging the marginal perforations of the two record strips R and M in order to advance them differential distances according to the settings of the two tape controlled devices UTC and LTC and according to the control cards of the printing tabulator. Other devices are provided in the form of adjustable drags or brakes for both strips and "end of sheet" detector levers for both sheets. The brakes act to keep the record material taut around the platen and the detector levers sense the end of either strip and stop card feeding to prevent printing when the record material is about to be exhausted from either supply source.

In Figs. 1 and 5 there is a general showing of the brake devices mounted in the rear of the carriage on a separate removable frame. Extending from the rear of the two main carriage frames 20 and 21 are projections 74 and 75 with

6 pairs of bolts 76 for receiving the slotted forward portions of side frames 77 and 78 of the braking unit.

Frames 77 and 78 are formed with vertical notches 79 and horizontal slots 80 whereby the entire brake unit may be easily removed by merely loosening the bolts 76 and sliding the frames up and back. To reassemble the unit, the procedure is merely reversed by sliding the unit forward and dropping the notched portions around bolts 76 before tightening them.

The brake unit side frames 77 and 78 are joined by two cross members or paper tables 81 and 82 which have overturned lugs 83, 84 and 85, Fig. 2, and are thereby fastened at their ends to the frames to hold them in spaced relation.

The upper table 81 acts as a support for the inner web of record material designated as register strip R which slides over the top of the table from right to left, Fig. 5, in going from the source of supply to the platen. Resting on the strip R is one or more of a series of three "end of sheet" detector levers 87 which are fastened to a common shaft 88 that is loosely pivoted in the side frames. Outside the right frame 78, Fig. 5, shaft 88 carries a lever 89, to one end of which is attached a spring 90 drawing it in a counterclockwise direction, and the other end of lever 89 cooperates with the underside of an insulation frame 91 pivoted at 92 and carrying a contact point in normal contact with a central spring blade comprising closed contacts 93.

Under the lower curved edge of each lever 87, Fig. 3, there is a slot 94 cut into the table 81, and, in the absence of strip R, spring 90, Fig. 5, is effective to rock levers 87 in a counterclockwise direction, also rocking lever 89 and frame 91 similarly to raise the upper contact point and break contacts 93, thus stopping the card feed as explained hereinafter. However, as long as record material R is present under any one of the three levers 87, the slot opening 94, Fig. 3, is bridged and the lever held up in the position shown in Fig. 5 to maintain contacts 93 in the normal closed running condition.

In the plan view, Fig. 1, it is seen that two "end of sheet" levers 87 are spaced in from the two sides of the brake unit. There is a third centralized lever 87 (not shown) which completes the coverage of detection to the whole width, so that regardless of the width of the form, or of its disposition at a right, left or central location, the passage of the end of it will be detected by one of the three levers.

The lower table 82 acts as a support for the outer web of record material identified as the main or check strip M which slides over the top of the table from right to left, Fig. 5, in going from the supply source to the platen. Resting on the strip M is one or more of a series of three "end of sheet" detector levers 87' which are fastened to a common shaft 88' which is loosely pivoted in the side frames. Levers 87' act to detect the presence or absence of strip M just as levers 87 do in cooperation with strip R, and the description already given of the construction and operation of the upper detector parts applies as well to the lower detector. It is believed sufficient to note that in the absence of strip M, a lever 89' lifts a frame 91' to break contacts 93'.

A box 96 is fastened to the outside of the right frame 78 to enclose the contacts 93 and 93'.

In cooperation with both webs of record materials R and M are separate brakes or drags to

keep the paper taut around the platen and prevent any tendency to pile up, buckle or jut out at the pin wheels, such a tendency being exhibited mainly on long feeding or eject operations when the web is accelerated out of the supply source and gathers momentum in going towards the platen. By placing brake shoes 98 and 99, Fig. 5, on the strips R and M, respectively, and pressing them down against tables 81 and 82, it is possible to put a drag on the record material to keep it taut at the printing and pin feeding positions.

Throughout this specification, when reference is made to a strip or web R or M, it is understood that either piece of record material may be of a single or multiple ply, and duplicated impressions thereon are made by carbon backings of outer sheets or separate carbon sheets interspersed between the record sheets. A customary form of inked ribbon is provided to place original impressions on the outer sheet.

Turning back to consideration of the brakes, it is noted in the enlarged view, Fig. 3, that shoe 98 is formed with upstanding front and rear walls, 100 and 101 which strengthen the shoe which is quite long, Fig. 1, in extending across the entire inside of the carriage. The rear wall 101 serves another purpose in that it is cut out at 102, Fig. 3, to act as a side guide for a thin flexible pressure blade 103, riveted at 104 to the top of the brake shoe 98. There are four such pressure blades 103, Fig. 1, evenly spaced across the shoe to distribute the applied pressure evenly. A slanted portion 105, Fig. 3, of the rear wall of the shoe, acts as a normal resting place for the similarly slanted section of blade 103.

The upper ends of blades 103 are riveted to the underside of shaft 106 and it is by the twisting of this shaft one way or the other that the pressure of the brake is increased or decreased.

Shaft 106, Fig. 1, is loosely pivoted in the side plates 77 and 78, and outside the left frame 77 there is assembled on the shaft, a loosely pivoted control lever 108. This lever 108 has an indirect connection to shaft 106 through a pressure adjustment lever 109, Fig. 3, which is pivoted thereon at 110 and has a pin and slot connection 111 with an arm 112 fastened to shaft 106.

Adjustment lever 109 is loosely pivoted at 110 on control lever 108, but it is adapted to be clamped thereon in a selected pressure regulating position. In the pointed end 113 of lever 108 there is cut an arcuate slot 114 through which passes the shank of a clamp screw 115, Fig. 4, which also passes through the end of adjustment lever 109 and carries a clamping nut 116 on the outside.

A pointer on the tip of adjustment lever 109 cooperates with an arcuately arranged set of adjustment marks 118 which act as indicators for the degree of brake pressure applied. For example, as shown, the lever 109 is centralized with respect to lever 108 to so position shaft 106 and the flexible blades 103 thereon, to apply a brake pressure found to suit the normal need. If it is desired to increase the brake pressure, then the nut 116 is loosened, lever 109 is rocked downward counterclockwise the desired degree, and nut 116 again tightened. In so moving lever 109 downward, the pin and slot connection 111 is raised, and arm 112 is rocked clockwise along with shaft 106 pinned thereto. Thus, the four flexible blades 103 are also rocked clockwise. Since the lower ends of the blades are secured at 104 to the brake shoe 98, they cannot move much, but the mid section is flexed to bear down on the

shoe and increase the drag on the record strip R which is pinched between the shoe and the top of table 81.

If it is desired to decrease the brake pressure, then nut 116 is loosened, lever 109 is rocked upward clockwise the desired amount, and nut 116 again tightened. When lever 109 is moved upward, the pin and slot connection 111 is depressed, and arm 112 is rocked counterclockwise along with shaft 106. This movement of the shaft serves to relieve some of the downward pressure of the blades 103 and as the shaft twists counterclockwise, pressure is taken off the brake shoe 98 and record strip R is relieved from some of the drag.

All the foregoing reference to the application and adjustment of braking pressure applies only while control lever 108, Fig. 2, is in the uppermost of three control positions. In such a position, a stop pin 119 on frame 77 limits the upward sweep of the point 113 to where it marks the control "Brake on—control on" which is an indication of normal running conditions with brake pressure applied and the "end of sheet" detection in operation. Lever 108 is maintained in the top position by a sliding plunger 125 which drops into a hole 126 in the side frame 77. In the large section, Fig. 4, it is seen that plunger 125 is formed with a knurled grasping head and is fitted in a hub 128 near the end of lever 108. A spring 127 in the hub, tends to keep the plunger point 126 extended, but it can be withdrawn from the side plate when the control lever 108 is to be swung down, Fig. 2, to either of the other two positions marked by the two arcuately arranged holes 121 and 122 also engageable by the plunger.

In the second position, Fig. 2a, it is seen that with lever 108 depressed slightly and located with plunger 125 in the locating hole 121, the entire brake assembly is rocked counterclockwise about shaft 106, and brake shoe 98 is lifted above table 81 and out of contact with the register strip R. The control lever points to the legend "Brake off—control on" to indicate that although the strip is free from pressure of the brake it is still contacted by the "end of sheet" detector lever 87 and that such control remains effective to stop card feeding when the end of strip R passes.

The control of the brake over the "end of sheet" detection lever 87, Fig. 3, is exercised through the contact of an overturned lug 129 on lever 87 with the top of the brake shoe 98. A slot 130 is cut into the wall 101 of shoe 98 and it is through this slot that the end of detection lever 87 projects upwardly to place lug 129 above the shoe and overlying a portion of the shoe. It will be remembered that there are three levers 87 on shaft 88, and therefore there are three slots 130 cut into the shoe to receive the levers.

It is noted in Figs. 2 and 2a that the two upper positions of lever 108 have no effect on detection lever 87; i. e. the lugs 129 remain poised above shoe 98 when it is raised slightly as well as when it is down on the strip R. However, when lever 108 is rocked still further into the third position, Fig. 2b, then the top of brake shoe 98 engages under lugs 129 and lifts the detection levers 87 slightly so that they no longer rest on the paper above slot 94, Fig. 3, and therefore cannot detect the passage of the end of the strip.

In the third position, Fig. 2b, it is noted that when lever 108 is depressed with a second degree of control movement, and located with plunger 125 in the locating hole 122, the entire brake

assembly and levers 87 are lifted above table 81 and out of contact with strip R. The control lever points to the indication "Brake off—control off" to show that the strip is free of both the drag and the "end of sheet" control and that the machine may be operated without the two restraints. Then the ordinary platen feed may be used or paper threaded around the lower pin wheels without any drag or control thereover.

Although the braking and controlling devices are described hereinbefore with reference to the upper control lever 108, shaft 106 and brake shoe 98, it is noted in Figs. 2 and 5 that a similar set of parts is associated with the lower brake shoe 99 in cooperation with the main strip M. These parts comprise detection levers 87', flexible blades 103' and control lever 108' with the pressure regulating parts 109' and 112'. Lever 108', Fig. 2, is also settable in three positions marked by holes 120', 121' and 122', for selection of braking and end of sheet control as already described. Therefore, although the two strips or sets of strips have a common platen and recording point, they have individual regulators for governing the extent of braking if any, and the control over strip detection.

It was pointed out hereinbefore with reference to Fig. 5 that contacts 93 and 93' are normally closed while strips R and M are feeding, one or the other of said contacts opening when the end of a related strip passes in front of detector lever 87 or 87'. The control exercised by these contacts 93 and 93' over the card feeding means of the tabulator is shown in Fig. 6. There it is seen that the two contacts are arranged in series with each other and in shunt around the start key contacts K1. When the start key is depressed, relay R12 is energized and closes contacts R12a to set up a holding circuit including line 320, stop key contacts K2, contacts 93' and 93, wire 325, relay contacts R12a, relay R12 and line 321. Therefore, as long as the stop key is not depressed, and as long as presence of record materials R and M keeps contacts 93 and 93' closed, relay R12 will remain energized. There are other controls in the circuit as shown in the application Serial No. 609,854, mentioned hereinbefore, but they are of little consequence in connection with the present controls. It is sufficient to note that relay R12 maintains energization of the card feeding clutch magnet CFCM as follows.

As long as relay R12 remains energized, it serves to close contacts R12b in series with cam contacts CB31 and relay R11 which when energized establishes a holding circuit through contacts R11a and cam contacts CB32. Relay R11 also closes contacts R11b which are in series with the card feed clutch magnet CFCM which maintains the driving connection between the constantly running parts of the tabulator and the card picker mechanism.

Whenever either or both of the contacts 93 and 93' open due to the passage of the end of a strip or strips, relay R12 is deenergized, causing the deenergization of relay R11 when contacts CB32 open. This causes the opening of contacts R11b and deenergization of clutch magnet CFCM which breaks the drive to the picker and stops the card feeding means.

While there have been shown and described and pointed out the fundamental novel features of the invention as applied to a preferred embodiment, it will be understood that various omissions and substitutions and changes in the form and details of the device illustrated and in

its operation may be made by those skilled in the art without departing from the spirit of the invention. It is the intention therefore to be limited only as indicated by the scope of the following claims.

What is claimed is:

1. In a card controlled printing device for printing on a plurality of strips of record material, a common platen around which said strips are drawn, a plurality of pin feeding devices for feeding said strips, means for operating said pin feeding devices, separate paper tables over which said strips pass in going from sources of strip supply to said platen, a brake shoe on each of said tables to press on the strip and provide a drag thereon, a control lever for raising said shoe to primary and secondary off positions, means cooperating with said control lever to adjust the pressure of said shoe, strip detector levers one of which is poised over a slot in each of said tables and passes through a notch in said shoe to rest on a record strip, normally closed contacts and control means therefor connected to each of said detector levers so that when the end of the strip passes beyond said slot, the detector lever drops in said slot and opens said contacts, a lug on said detector lever cooperating with said shoe on the side of said notch to lift said detector lever above said strip out of control position when the control lever is put in the secondary off position, a card feed control means, and means controlled by said contacts to disable said card feed control means to stop card feeding when the end of a strip passes the braking position.
2. In a record feeding device, a paper table over which said record passes, a brake shoe for pressing on the record on the table, a brake shaft, a series of flexible blades connecting said shoe to said shaft, a control lever loosely mounted on said shaft, an arm fastened to said shaft, a pressure adjustment lever pivoted on said control lever and having a pin and slot connection with said arm, means for fastening said adjustment lever to said control lever in any of a plurality of adjusted positions, and means for holding said control lever in positions wherein said brake shoe is effective or raised to an ineffective off position.
3. In a record feeding device, a paper table over which said record passes, a detector lever a portion of which rests on said record over a slot in said table which allows the lever to move when the end of said record passes, stopping controls under control of said lever and effected when the end of said record passes, a brake shoe for pressing on the record on the table, a control lever with connections to said shoe to lift it to an off position, and connections between said detector lever and said shoe whereby the detector lever is lifted away from the record to an ineffective position when the shoe is lifted to an off position.
4. In a record feeding device, a platen, main side frames in which said platen is supported, upper and lower pin feed devices supported above said platen, a removable frame for said lower pin feed device comprising a pair of cross shafts, slot and hook formations on the top of said main side frames for engaging the ends of said cross shafts, manipulative detents pivoted on said main frames and cooperating with one of said shafts to hold said pin frame down on said main frames, an auxiliary removable frame for said upper pin feed device with cross shafts and pivot studs,

11

notches and hook formations on the top of the lower removable frame for receiving a cross shaft and the pivot studs of the upper removable frame, and a pair of positioning latches pivoted on the lower frame and cooperating with a cross shaft of the upper frame to hold the upper pin feed device in a lowered or a raised position.

5. The combination set forth in claim 4 wherein said latches are spring urged and have notches facing the hook formations on the lower frame, whereby pressure of the latches on the cross shaft of the auxiliary frame tends to hold the pivot studs in said hook formations.

6. The combination set forth in claim 1 with means for holding said control lever in one of three control positions; in the first of which positions both the brake and the detector lever

12

are effective, in the second or primary off position only the brake is made ineffective while the detector lever is still effective, and in the third or secondary off position both the brake and the detector lever are made ineffective.

FRANK J. FURMAN.
